CANDLE CHANDELIER MOBILE

Edwin T. Blake, East Fishkill, N.Y.
(Rte. 376, Hopewell Junction, N.Y. 12533)

Filed Feb. 14, 1972, Ser. No. 226,388

Term of patent 14 years

Int. Cl. D26—01; D11—02

U.S. Cl. D48—2

FIG. 1

FIG. 2

FIG. 1 is a perspective view of a candle chandelier mobile showing my new design; and,

FIG. 2 is a perspective view of a second embodiment of my new design.

The candles are shown in broken lines in FIGS. 1 and 2 for illustrative purposes only.

I claim:

The ornamental design for a candle chandelier mobile, as shown and described.
